DESK LAMP

Michael S. Lax, New York, N.Y., assignor to Lightolier Incorporated, New York, N.Y., a corporation of New York

Filed Dec. 7, 1965, Ser. No. 105

Term of patent 14 years

(Cl. D48—20)

FIG. 1

FIG. 2

FIG. 3

FIG. 4

FIG. 5

FIG. 6

FIG. 1 is a side elevational view of the desk lamp showing my new design in open position;

FIG. 2 is an end elevational view thereof;

FIG. 3 is a top plan view thereof;

FIG. 4 is a bottom plan view thereof;

FIG. 5 is a perspective view showing the desk lamp with the reflector in one of its operative positions, and

FIG. 6 is a perspective view showing the desk lamp in collapsed position.

The dominant features of my design reside in the portions shown in full lines.

I claim:

The ornamental design for a desk lamp, substantially as shown and described.
